UNITED STATES PATENT OFFICE.

ANDREW J. STEEL, OF NEEDLES, CALIFORNIA.

WRINGER-SUPPORT.

1,189,012.

Specification of Letters Patent. Patented June 27, 1916.

Application filed August 19, 1915. Serial No. 48,292.

To all whom it may concern:

Be it known that I, ANDREW J. STEEL, a citizen of the United States, residing at Needles, in the county of San Bernardino and State of California, have invented certain new and useful Improvements in Wringer-Supports, of which the following is a specification.

This invention relates to clothes washers and wringers, and pertains especially to a wringer attachment.

The object of the invention is to provide a bracket for a swinging wringer, and to furnish a novel and peculiar device for locking the wringer in wringing position.

Other objects, advantages and improved results will be found in the practical application of the invention.

In the accompanying drawings forming part of this application:—Figure 1 is a side elevation showing the movable position of the wringer in dotted lines. Fig. 2 is a central sectional view. Fig. 3 is an elevation looking at the back of the washboard, and showing the tub extension. Fig. 4 is a detail perspective view of part of the washboard and the part of the tub having the extension. Fig. 5 is a detail perspective view of the locking device for the wringer. Fig. 6 is a perspective view of a modification.

The same reference characters denote the same parts throughout the several views of the drawings.

In carrying out my invention I employ a wash tub 1, which may be of any size and composed of any suitable material. An extension 2 projects at an angle to and from the top edge or periphery of the tub and forms a supporting rest 3 for the washboard 4, upon the tub. The angle of the extension or support 3 is such as to position the board in the tub on a proper and convenient incline for rubbing clothes thereon in a washing operation. The board is attached to the support by suitable bolts 5 extending through the board and the extension, and said bolts are provided with suitable nuts 6.

The wringer comprises the usual rollers 7, journaled in the wringer frame 9, and the rollers are provided with gear wheels 10, operated by a crank handle 11. The sides of the wringer frame are extended so as to provide a pair of bracket arms 12, pivoted to the sides of the washboard on a rod 2^a, above the periphery of the tub so that the

free ends of the arms will not come in contact with the tub or other bracket support in the pivot or swinging movement of the bracket and the wringer carried thereby. 60 The sides of the washboard have legs 13 fitting within the tub. The gears are inclosed by casings 1^a. It will be observed that the washboard forms a support for the wringer bracket and for the locking device herein-after particularly described, but the bracket and said device may be supported by any other suitable means.

The wringer bracket co-operates with a device for locking the bracket and the wringer in upright position, and consists of a pair of slidable bars 14, working through straps 15 secured to the back of the washboard, and said bars are pivoted to a pair of hand levers 15^a, each of which is fulcrumed 75 at 16 to the support 4. The adjacent ends of the levers 15^a, have a flange 17 forming a hand grasp. The outer end of the bars is provided with a pintle 19 for engaging a hole 20 in the end of each of the arms 80 12, and for holding the wringer locked in vertical wringing position.

The wringer may be operated in substantially horizontal position by swinging the wringer downwardly until the top portion 85 of the wringer frame engages the top edge or periphery of the tub, as shown in dotted lines, Fig. 1, and in this position the wringer rollers may be operated by the handle 11 without engaging the tub. In this position 90 the pintles of the bars 14 project under the pivot end of the arms 12 and prevent upward movement of the wringer. The wringer is shown hanging upon the outside of the tub, in dotted lines, Fig. 1, and in 95 this position the pintles of the bars 14 prevent upward movement of the wringer. Obviously, the bars must be operated first in order to free the wringer for swinging into out of its various positions.

Referring to Fig. 6 of the drawings, a supporting rest 21 is secured to the back of the washboard 22, and may be clamped to an ordinary tub 23, by means of set screws 24, for attaching the board and its 105 wringer 25, to the tub in proper washing and wringing positions. By this arrangement the washboard carries the supporting rest instead of the rest being formed on the tub, and the same results are attained.

It will be seen that the wringer and the washboard are attached to the tub in operative

position by securing the washboard to the tub extension, and that in either form of attachment the proper angle of the washboard is predetermined and fixed by the supporting rest.

I do not wish to confine myself to any particular size or material in the practical application of my invention, but reserve to myself the right to make such changes and 10 variations therein as may come within the scope of the appended claim.

Having thus described my invention what I claim as new and desire to secure by Letters Patent is:—

A swinging bracket for wringers comprising 15 arm extensions of the side frames of the wringer, a support to which the arms are pivoted, and a locking device comprising a pair of hand levers fulcrumed to the support, and a pair of levers pivoted to the 20 hand levers and slidably connected with the support for co-operating with said arms.

In witness whereof I hereunto set my hand in the presence of two witnesses.

ANDREW J. STEEL.
